T. LA TESSA

LAMP SPINDLE OR SIMILAR ARTICLE

Filed Jan. 19, 1928

Witness:

Chas. R. Koursh.

Inventor,

Tully La Tessa,
by Marion C. McElroy

UNITED STATES PATENT OFFICE.

TULLY LA TESSA, OF CHICAGO, ILLINOIS, ASSIGNOR TO H. A. BEST LAMP COMPANY, A CORPORATION OF ILLINOIS.

DESIGN FOR A LAMP SPINDLE OR SIMILAR ARTICLE.

Application filed January 19, 1928. Serial No. 24,929. Term of patent 3½ years.

To all whom it may concern:

Be it known that I, TULLY LA TESSA, a citizen of the United States, residing in Chicago, county of Cook, and State of Illinois, have invented a new, original, and ornamental Design for a Lamp Spindle or Similar Article, of which the following is a specification, reference being had to the accompanying drawing, forming part thereof.

The figure is a view in elevation of a lamp spindle or similar article, showing my new design.

I claim:

The ornamental design for a lamp spindle or similar article, as shown.

TULLY LA TESSA.
